UNITED STATES PATENT OFFICE

ARTHUR A. G. LAND, OF CHICAGO, ILLINOIS

MESH-SECTIONED WIRE FABRIC

Application filed April 11, 1929. Serial No. 354,224.

I am aware of prior wire fabrics in which all constituent strands extend longitudinally of the fabric, which fabrics include straight strands around which other (and usually 5 lighter) strands are twisted for one more turn; so that the heavier strands take the tensioning strain when such a fabric is erected in a fence, and also support the lighter wires.

10 However, these prior fabrics cannot be rolled up for shipment when made in long lengths, unless the straight strands are of such flexibility as to make them unsuited for forming a rigid fence, and cannot be cut 15 into lengths or spliced without using cutting tools or without leaving unsightly joints. So also, the straight wires in these prior fabrics would be horizontal in an erected fence, thereby increasing the toe-hold (for 20 any one wishing to climb the fence) over that which would otherwise be afforded by the meshes which they apparently intersect.

In the presented fabric, the mesh-sectioning wires greatly reduce the toe-hold in the 25 meshes bisected by them, so that these meshes can be much wider than would otherwise be permissible in a fence. So also, since my upright mesh-sectioning wires interlock with consecutive vertically spaced pairs of 30 bights in the fabric, these sectioning wires prevent a vertical contraction of the meshes bisected by them; consequently, they greatly increase the longitudinal strength of the fabric, since meshes cannot be spread longitudinally of the fabric without correspondingly 35 contracting them vertically.

It will also be noted that the term "bight" 40 is used in the appended claims to denote substantially U-shaped bends each of which extends only for a fraction of a turn around another strand, as distinguished from so-called twists made by wrapping one wire around another wire for one or more complete turns.

45 Moreover, with my fabric, the zigzag strands which form the bisected meshes need not be changed in any manner, since the bisecting wires loop around them; so that the only special equipment required is that for 50 forming these bisecting wires with the need-

ed bends, two types of which bends are shown respectively in Fig. 2 and in Fig. 10.

My invention relates to chain link wire fabrics, and in its general objects aims to provide an inexpensive wire fabric of this class 55 which will afford unusually small mesh openings in proportion to the amount of wire in the fabric and the cost of the fabric.

As heretofore manufactured, chain link wire fabrics are commonly composed of 60 wires preformed into flattened spirals or so-called zigzag strands having parallel axes, the consecutive strands in the fabric being intertwisted for relatively interlocking the adjacent bights in the strand, thereby forming 65 parallel rows of meshes. The resulting meshes are usually four-sides and each substantially of the shape of a square of diamond which in an erected fence or grille has two opposite corners respectively at the top and 70 the bottom of the mesh.

When employed for fences, grilles or the like, the utility of such a fabric depends both on its rigidity and on the size of the mesh 75 openings, since the effective size of each mesh opening determines the size of object which can pass through the mesh and also determines the extent to which any one could secure a foothold in the mesh when attempting to climb upon it. Owing to this determining effect of the size of the mesh openings, chain link wire fabrics intended for many purposes have heretofore required a far greater number of intertwisted strands for a given length of the fabric than would 85 be needed to afford the desired rigidity. This increased number of the constituent strands involves an undesirably high cost both for the required amount of wire, the cost of intertwisting so many wires, and the 90 transportation expenses.

My present invention aims to reduce these costs by providing wire fabrics in which the effective mesh openings are greatly reduced in size in proportion to that of the zigzag 95 formations in the main strands of the fabric, and accomplishes this purpose by subdividing or sectioning the usual meshes in such fabrics. Moreover, my invention provides a mesh-sectioned chain link wire fabric in 100

which the mesh-sectioning wires do not add to the weight or cost of the fabric in proportion to the reduction in the mesh openings which is attained by their use, and in which these mesh-sectioning wires are securely held in their operative positions without requiring auxiliary fastening means.

In its further objects, my invention aims to provide mesh-sectioned fabrics of this class which are easily manufactured, which can be rolled up in the usual manner for compact shipment, and which can be manufactured with the greater portion of the fabric constituted by flattened spiral (or so-called zigzag) strands of the ordinary type which is commonly employed for chain link wire fences. My invention also provides a mesh-sectioned fabric of this class in which both ornamental effects and a still further reduction in the effective size of the mesh openings can be secured by merely preforming auxiliary bends in part or all of the constituent wire portions. Moreover my invention aims to provide a mesh-sectioned fabric of this class, in which the connection of the mesh-sectioning wires to the zigzag main strands forming the sectioned meshes is independent of the connection of these strands to each other; and in which these mesh-sectioning wires are so interlocked with the main strands that the portion of each such wire which sections a mesh forms a strut to prevent an expanding of that mesh in a direction transverse of that wire and longitudinally of the fabric.

Furthermore, my invention aims to provide a mesh-sectioned wire fabric in which the sectioning of the meshes is effected by preformed wires attached to the main mesh-forming strands of the fabric so that these wires do not take up any space between the zigzag main strands, thereby permitting the sectioning to be done only in selected portions of the fabric when desired, and also permitting the selective use of mesh-sectioning wires presenting parts of varying shape within the sectioned meshes.

So also, my invention provides a simple and expeditious method for assembling such mesh-sectioned fabrics. Moreover, my invention provides a mesh-sectioning applicable in connection with ordinary chain link wire fabrics and adapted to afford sectioned meshes in selected parts of the fabric, so that the resulting fabric will only have the effectively smaller meshes in the portions where the smaller meshes are needed.

Still further and also more detailed objects will appear from the following specification and from the accompanying drawings, in which

Fig. 1 is an elevation of a portion of a mesh-sectioned chain link wire fabric embodying my invention.

Fig. 2 is an enlargement of a portion of Fig. 1, showing the intertwisting of bent por-

tions of a mesh-sectioning wire with the usual bights in two adjacent flattened spiral or so-called zigzag strands.

Fig. 3 is an elevation of a portion of a mesh-sectioned fabric in which the mesh-sectioning wire is crinkled to effect a further reduction in the size of each half of each sectioned mesh.

Fig. 4 is an elevation of a portion of a mesh-sectioned fabric in which all of the zigzag strands have auxiliary formations for augmenting the effective mesh-aperture reduction, while the mesh-sectioning wires have no such auxiliary formations.

Fig. 5 is an elevation of a portion of a wire fabric in which pairs of zigzag strands of the ordinary formation alternate with pairs of zigzag strands provided with auxiliary formations for reducing the openings in the meshes bordered by them; and in which mesh-sectioning wires effectively bisect certain rows of the resulting meshes.

Fig. 6 is an elevation of a portion of a wire fabric in which both the zigzag strands and the mesh-sectioning strands have auxiliary formations for reducing the effective apertures of the resulting mesh sections.

Fig. 7 is a fragmentary elevation of a wire fabric in which mesh sectioning wires of another form are employed.

Fig. 8 is an enlarged and fragmentary transverse section taken along the line 8—8 of Fig. 7, showing how each bend in this wire overhangs bight portions of the zigzag strands.

Fig. 9 is a fragmentary elevation of a fabric allied to that of Fig. 7, but having the bends of the mesh sectioning wires approximately in the general plane of the fabric.

Fig. 10 is an enlargement of the right-hand upper portion of Fig. 9.

Fig. 11 is an enlarged and fragmentary section taken along the line 11—11 of Fig. 9.

Fig. 12 is a diagrammatic view showing a portion of a fabric in which only the lower meshes are sectioned after the manner of the meshes of Fig. 1 or Fig. 7, and in which each mesh-sectioning wire is hooked at its upper end over a juncture of two zigzag strands.

Fig. 13 is an elevation of a portion of a wire fabric formed of an embodiment of my invention in which only the lower part of each vertical row of the meshes formed by the zigzag strands is sectioned, and in which each mesh-sectioning strand projects upwardly into such a mesh.

Fig. 14 is a fragmentary elevation of a fabric in which each mesh-sectioning strand consists of two wires which have portions within each mesh bent apart.

In accomplishing the purposes of my invention after the manner of Fig. 1 and of the laterally medial portion of Fig. 5, I employ as the main strands A and B of the fabric the usual flattened spirals or so-called zigzag strands used for making ordinary chain link

wire fences or the like. Then I also employ auxiliary or mesh-sectioning strands C which are straight except for S-shaped portions 1 formed in them, each of these S-shaped portions desirably having its parts so spaced that the intertwined bights of the two adjacent main strands can extend respectively through its two bends.

These S-shaped portions have their middle points spaced by the uniform mesh height 2 of the zigzag strands, namely the distance longitudinally of each zigzag strand between the centers of two consecutive bights at the same edge of the strand, and all of the S formations may lie approximately in the same plane.

In manufacturing such a fabric, the mesh-sectioning wire C can first be slid endwise through the consecutive bights 3 shown at 20 the right-hand edge of the first or left-hand zigzag strand of Fig. 1, with the wire C extending in the same direction through the consecutive bight in the wire of the strand A. When the mesh-sectioning wire has been inserted for a sufficient distance so that each of its S-shaped portions is opposite one of the right-hand bights 3 of the zigzag strand A 1, the next zigzag strand B is intertwined with the strand A by the usual spirally advancing movement of the strand B, in doing which each bight 3 of the strand B twists also around a part of an S-shaped portion 1 of the mesh-sectioning wire C.

When the zigzag strand B has thus been intertwined with both the adjacent zigzag strand A and the mesh-sectioning wire C, the free ends of the strands A and B are secured to each other, as for example by intertwisting them, and each free end of the wire C also secured to at least one of the two zigzag strands with which it is intertwined. For this securing, I desirably intertwist the alternate mesh-sectioning wires C with the upper ends of the zigzag strands A and B which border the vertical row of meshes sectioned by the wire C to form twists 5, while each free end of the interposed mesh-sectioning wires C may simply be hooked over the uppermost interlocked bights of the strand B and the next strand A, as shown at 6 in Fig. 1. The twists 5 and the hooks 6 then cooperate with the joint intertwisting of the strands and wire forming a vertical row of sectioned meshes, which intertwisting is shown on a larger scale in Fig. 2, for retaining the sectioning wires in their proper position while the fabric is rolled up and shipped.

These mesh-sectioning wires C can also be inserted between the zigzag strands A and B after they are spirally assembled in the usual manner and before ends 5 are twisted together.

Then when the fabric is tensioned longitudinally (or laterally in Fig. 1) during its

erection for a fence or the like, the bights of each two adjacent zigzag strands A and B interlock with a spiral portion of the associated mesh-sectioning wire C, as shown in Fig. 2. What is more, a part 7 of each S-shaped portion of the wire C seats on an inclined portion of the strand B, while a lower parts seats on an inclined portion of the strand A, so that the mesh-sectioning wire is also supported by bight portions of both of the zigzag strands associated with it. Consequently, each mesh-sectioning wire is rigidly and securely held in the erected fabric, the fastening of its ends being merely required for retaining this wire in position before the fabric is erected. Moreover, it will be seen from Figs. 1 and 2 that the bights of the adjacent zigzag strands interlock directly with each other and that the mesh-sectioning wires do not take up any room between these bights of adjacent strands. This not only enables me to employ the ordinary zigzag strands as commonly manufactured for chain link wire fabrics, but also permits me to mesh-section any desired part of a chain link wire fabric of the ordinary type without requiring any change in the formation of the zigzag wires.

When the fabric is in use, it will be seen from Fig. 1 that each ordinary square mesh formed by the zigzag strands is bisected by a mesh-sectioning wire C, thereby greatly reducing the resulting mesh openings. For example, the maximum diameter of a ball 8 which would pass through one of the resulting triangular meshes is only about half of that of the ball 12 which would pass through the meshes formed by the same zigzag strands if the mesh sectioning wire had not been added.

To exclude balls of the same diameter as the ball 8 with an ordinary chain link wire fabric would require much more wire than that needed for the mesh-sectioned fabric of Fig. 1, and also would require more labor in the 100 assembling of the fabric, since it takes less time to insert a mesh-sectioning wire than it does to intertwist one zigzag strand with another one. Consequently, my fabric requires less wire for a given object-excluding effect, 115 and also costs less for labor per running foot.

Moreover, while I have heretofore described an embodiment formed of simple zigzag strands having straight legs connecting their bights, together with generally straight mesh-sectioning wires, I do not wish to be limited to the form of the wire portions between the bights in each of these strands or wires. Indeed, I can enhance both the guard effect of the fabric and the appearance of the fabric by preforming its constituent parts through the addition of suitably disposed simple bends.

For example, a further reduction in the effective apertures of each half of a sectioned

mesh will be produced by providing S-shaped crinkle formations 9 in each part of a mesh-sectioning wire C between consecutive bights of the latter, as shown in Figs. 3 and 6; or by providing the legs (or parts connecting the consecutive bights of the zigzag strands) with auxiliary formations 10, as shown in Figs. 4 and 5. Or, I may provide such auxiliary formations in all three of the strands or wires constituting each row of sectioned meshes as shown in Fig. 6. These auxiliary formations preferably are formed to extend in the general plane of the fabric and can easily be designed so as to afford an ornamental appearance to the fabric, as shown in Figs. 4 and 6.

However, while I have illustrated my invention in connection with fabrics having formations of desirable shapes formed in the constituent strands or wires, and having S-shaped portions of each mesh-sectioning wire intertwined with the bights of adjacent zigzag strands, I do not wish to be limited in this respect, nor as to other details of the construction and arrangement above disclosed. Neither do I wish to be limited to the employment of my mesh-sectioning wires in every portion of a fabric, since these might be used only for selected fabric portions.

For example, in the embodiment of Figs. 7 and 8, the fabric of my invention comprises zigzag strands A and B having the bights of the consecutive strands interlocked in the usual manner, and the mesh-sectioning wires D do not intertwist with these bights of the zigzag strands. Instead, each mesh-sectioning wire D has substantially U-shaped bends 11 looping over the interlocked bights of the zigzag strands forming the meshes which are bisected by that wire D. The consecutive bends 11 extend respectively in opposite directions but may all lie in a common plane, and the main parts of the wire D pass consecutively forward and rearward of the mesh-strand portions. In making this fabric the mesh-sectioning wire D is placed adjacent to the spiral strand A in Fig. 7 and the strand B is intertwined in the usual manner with the strand A and inside the U-shaped portions 11 of the mesh-sectioning wire D, after which the ends of each wire D are secured to adjacent zigzag strands as by an intertwist 5 or hook 6.

Then when the wire D has its ends secured to the zigzag strands, the resiliency of the wire straightens it and presses each bend 11 against the interlocked bights adjacent to that bend, so that a portion of each bend can hook around a zigzag strand portion (as shown in Fig. 8) to aid in supporting the mesh-sectioning wire.

In the embodiment of Figs. 7 and 8, the bends in the mesh-sectioning wires all lie approximately in planes approximately at right angles to the general plane of the

fabric. However, my fabric may also be constructed with the bends 11 of the mesh-sectioning wires all lying approximately in the general plane of the fabric, as shown in Figs. 9, 10 and 11.

With both the types of Figs. 1 to 6 and those of Fig. 7, the zigzag strands have their bights directly interlocked in the ordinary manner of chain link fabrics and these alone would form larger meshed fabrics if the mesh-sectioning wires were omitted. Consequently, such larger meshes may be left unsectioned in any selected part or parts of the fabric. Thus, Figs. 12 and 13 show portions of fabrics in which the mesh-sectioning wires terminate below the upper meshes, so that only the lower meshes are sectioned, for which purpose the mesh-sectioning wires of both Fig. 1 and Figs. 7 and 9 are suitable. Such partially mesh-sectioned fabrics are particularly suited for fences where effectively small meshes are needed only in the lower portion—as for example, in order to keep out small chicks—and my invention provides a single fabric for such fences instead of the heretofore customary use of two separately formed fabrics having meshes of different sizes.

In each of the illustrated embodiments, the directly interlocking bights of the zigzag strands receive the strain when the fabric is tightened by stretching it longitudinally.

The mesh-sectioning wires do not interfere with this tightening, but increase the stiffness of the fabric at right angles to its general plane, even if these wires are of smaller diameter than the zigzag strands.

With the illustrated embodiments, and particularly with those of Fig. 1, 7, 9, 12, and 13, the part of each mesh-sectioning wire which extends across a mesh formed by two consecutive strands serves as a strut to prevent a shortening of the mesh in a direction parallel to the axes of these strands, or vertically in these figures. Consequently, when my mesh-sectioned fabric is tensioned longitudinally of the fabric (or horizontally in each of these figures), these mesh-sectioning wires resist a horizontal spreading of the meshes, thereby permitting thinner and lighter strands to be employed for withstanding a given degree of tensioning with any given size of meshes.

However, since the mesh-sectioning wires do not extend between the intertwined bights of the main zigzag strands but are partially twisted or looped around these intertwined bights (namely through arcs of not over 360 degrees), as shown in Figs. 2 and 10, this addition of mesh-sectioning wires to the zigzag mesh-forming strands does not interfere with the affording of a hinging connection by the intertwining of these main strands. Consequently, when both the main strands and the mesh-sectioning wires extend trans-

versely of the fabric, my fabric can be manufactured in any desired lengths (as for example, lengths of several hundred feet) and rolled up for compact storage and shipment even when both the main zigzag strands and the mesh-sectioning wires are so stiff that they could not easily be bent, which could not be done if the constituent strands extended longitudinally of the fabric.

10 Furthermore, it should be understood that I have used the term "mesh-sectioning wire" in a generic sense in which it is not limited to a single wire, as a strand or group of wires may be employed for the same purpose. 15 For example, Fig. 14 diagrammatically shows an embodiment of my invention in which each mesh-sectioning strand consists of two wires E which are adjointed adjacent to the bights of the zigzag strands A and B but spread 20 apart in the middle portion of each sectioned mesh. By forming these wires E so that their bent portions bow away from each other and assembling the fabric so that these bent portions all lie in the general plane of the 25 fabric, I effectively trisect each mesh, thereby greatly reducing the effective mesh-section apertures.

I claim as my invention:

1. A wire fabric comprising upright zigzag strands having the bights at the adjacent sides of two consecutive strands directly spirally intertwined so that the two strands border a row of meshes; and vertical mesh sectioning wires each extending substantially medially of such a row of meshes, and through the said intertwined bights of both of the zigzag strands, each mesh-sectioning wire having bent portions consecutively interlocking with and seated upon two zigzag strands 40 bordering the row of meshes medial of which that mesh-sectioning strand extends, the interlocking of each mesh-sectioning wire with the two strands forming the meshes sectioned by that wire being independent of the intertwining of the said two strands.

2. A wire fabric comprising zigzag strands spirally intertwined to form parallel rows of meshes, and mesh-sectioning wires each extending longitudinally of one of the said rows across the meshes of that row for effectively sectioning these meshes, each such mesh sectioning wire passing alternately forwardly and rearwardly of one of the zigzag strands forming the row of meshes across which that mesh-sectioning strand extends and exteriorly of the intertwining of the two strands forming the said row.

3. A wire fabric comprising zigzag strands having the bights of consecutive strands being directly intertwined so that every two consecutive strands border a row of meshes, and mesh-sectioning wires each substantially bisecting one such row of meshes, each mesh-sectioning wire having spaced bends respectively interlocked with portions of the two

adjacent strands independent of the intertwining of these strands, and each mesh-sectioning wire having adjacent to the middle of each mesh bisected by it a substantially S-shaped bend portion for reducing the effective object-excluding size of both of the half-meshes into which that mesh is divided by the mesh-sectioning wire.

4. An upright wire fabric comprising upright flattened spiral strands presenting consecutively diverging legs connected to one another by bights, each of which bights extends through an arc of not more than 360 degrees when viewed from an end of the strand, each strand being spirally twined through an adjacent strand so as directly to interlock bights of these two strands, whereby each two adjacent strands form an upright row of meshes; and upright mesh-sectioning wires respectively extending medially of each such row; each mesh-sectioning wire having spaced bends adjacent to and interlocked with the interlocked strand portions at the upper and lower ends of each mesh of that row, and each such bend being exterior to the interlocked strand portions to which it is adjacent.

5. An upright wire fabric comprising upright flattened spiral strands presenting consecutively diverging legs connected to one another by bights, each of which bights extends through an arc of not more than 360 degrees when viewed from an end of the strand, each strand being spirally twined through an adjacent strand so as directly to interlock bights of those two strands, whereby each two adjacent strands form an upright row of meshes; and upright mesh-sectioning wires respectively extending medially of each such row; each mesh-sectioning wire having portions thereof respectively adjacent to and twisted for not more than one full turn about and exteriorly of the directly interlocked bights at a corner of each mesh of the row with which that mesh-sectioning wire is associated.

6. An upright wire fabric comprising upright flattened spiral strands presenting consecutively diverging legs connected to one another by bights, each of which bights extends through an arc of not more than 360 degrees when viewed from an end of the strand, each strand being spirally twined through an adjacent strand so as directly to interlock bights of those two strands, whereby each two adjacent strands form an upright row of meshes; and upright mesh-sectioning wires respectively extending medially of each such row; each mesh-sectioning wire having bends exterior to and respectively curved around interlocked portions of the two strands forming the meshes of one row, and having substantially S-shaped bends disposed substantially central of meshes of that row, the said

bends lying substantially in the general plane of the fabric.

7. A mesh-sectioned wire fabric comprising axially parallel zigzag strands consecutively intertwined so as to afford a hinging connection between each two consecutive strands and so that each two consecutive zigzag strands border a row of meshes; and mesh-sectioning wires each extending medially of such a row of meshes, each such wire having spaced bends respectively interlocked with the intertwined junctures of the two strands forming that row of meshes so that each sectioning wire portions forms a strut extending across a mesh; the said bends being of such form and extent as not to interfere with a movement of the row-forming strands about their said hinging connection, thereby permitting a rolling and unrolling of the fabric about an axis parallel to the axes of the said mesh-sectioning wires.

Signed at Chicago, Illinois, April 9th, 1929.
